[57] CLAIM

The ornamental design for a vehicle tire, as shown and described.

DESCRIPTION

FIG. 1 is a perspective view of a vehicle tire showing our new design, it being understood that the tread pattern is repeated throughout the circumference of the tire;

FIG. 2 is an end elevational view thereof;

FIG. 3 is a side elevational view thereof, the opposite side being a mirror image of that shown; and

FIG. 4 is a sectional view thereof taken along line 4—4 in FIG. 2.

FIG. 1

FIG. 2

FIG. 3

FIG. 4
